DESIGN FOR A TOILET BOTTLE

Lawrence J. Kihm, Pittsburgh, Pa., assignor to Maison Joubert, Inc., New York, N. Y., a corporation of New York

Application February 19, 1938, Serial No. 75,258

Term of patent 14 years

To all whom it may concern:

Be it known that I, Lawrence J. Kihm, a citizen of the United States of America, residing at Pittsburgh, county of Allegheny, and State of Pennsylvania, have invented a new, original, and ornamental Design for a Toilet Bottle, of which the following is a specification, reference being had to the accompanying drawing, forming a part thereof.

I claim:

The ornamental design for a toilet bottle as shown.

LAWRENCE J. KIHNM.
